US00D495995S1

(12) United States Design Patent (10) Patent No.: **US D495,995 S**
Moriyama et al. (45) Date of Patent: **** Sep. 14, 2004**

(54) **LOWER CAGE OF A TRANSCEIVER CAGE ASSEMBLY**

6,478,622 B1 * 11/2002 Hwang 439/607

* cited by examiner

(75) Inventors: **Keiko Moriyama**, Aichi (JP); **Byung Yong Kim**, Aichi (JP); **Michael Kandros**, Aichi (JP)

Primary Examiner—Philip S. Hyder

(74) Attorney, Agent, or Firm—Osha & May L.L.P.

(73) Assignee: **J.S.T. Mfg. Co., Ltd. (JP)**

(57) CLAIM

(**) Term: **14 Years**

The ornamental design for a lower cage of a transceiver cage assembly, as shown and described.

DESCRIPTION

(21) Appl. No.: **29/174,516**

(22) Filed: **Jan. 21, 2003**

(30) **Foreign Application Priority Data**

Aug. 1, 2002 (JP) 2002-020676

(51) LOC (7) Cl. **13-03**

(52) U.S. Cl. **D13/133**

(58) Field of Search D13/133, 154; 439/607, 608, 609, 610, 939; 385/92, 89

FIG. 1 shows a bottom view of a lower cage of a transceiver cage assembly.

FIG. 2 shows a top view of a lower cage of a transceiver cage assembly.

FIG. 3 shows a left-side view of a lower cage of a transceiver cage assembly.

FIG. 4 shows a right-side view of a lower cage of a transceiver cage assembly.

FIG. 5 shows a front view of a lower cage of a transceiver cage assembly.

FIG. 6 shows a rear view of a lower cage of a transceiver cage assembly; and,

FIG. 7 shows a perspective view of a lower cage of a transceiver cage assembly. The broken line showing of an upper cage is for illustrative purposes only and forms no part of the claimed design.
